UNITED STATES PATENT OFFICE

JOHN LEO SCHALLER, OF WELLESLEY, MASSACHUSETTS

ROOF JOINT

Application filed August 19, 1925. Serial No. 51,262.

The subject matter herein involves the roof joint so-called, the same being the seal between the roof itself and any protruding pipe or vent. The problem of sealing a vertical pipe in a roof which may be built in or assume by settling any variety of slant is a serious one. For any roof of definite angle it is easy to provide sealing members, but roofs vary in specification and in resultant execution.

One answer is to build a roof absolutely uniform to a given pitch and keep it so. The seal could then be provided.

In practice there are two ways of dealing with the problem. One is to provide a considerable number of joints, each adapted to a given pitch or approximations thereof. The other is to provide a joint which can be cut over or refitted to adapt it to various pitches.

It has been attempted to provide a joint in which there were certain adjustments possible, but as far as I am advised these have been of a limited nature.

My present invention contemplates a roof joint in which two cooperating parts provide a maximum range of angle variance. The provisions for this feature together with various specific improvements constituting my invention will be more clearly set forth in the specification which follows.

As illustrative of my invention I have shown in the accompanying drawings a form of my invention well adapted to practical use and I have attempted to illustrate the principles thereof diagrammatically to show the wide variations in which the invention proper might be applied, adapted or embodied.

The more general aspect of my invention involves bearing surfaces inclusive of various bearing lines which are figures of conic section of considerable variety. These are difficult to show but readily understood by those familiar with such figures. To make this clear I will proceed to a discussion of the embodiment shown in the drawings in which like reference characters are used to indicate the parts described in the specification. In the drawings:

Fig. 1 is a side elevation of a roof joint, partly broken away.

Fig. 2 is a plan view thereof.

Figs. 3, 4 and 5 are views illustrative of different adjustments.

Figs. 3^a, 4^a and 5^a are diagrammatic developments of Figs. 3, 4 and 5, respectively.

Figs. 6 and 7 are sections on the lines 6—6 and 7—7 respectively, of Fig. 3, and

Fig. 8 is a detail view of a splittable packing ring used with my invention.

Referring now to the drawings, it will be seen that I provide the usual roof plate 1 which is apertured for the passage of a pipe, such as 2. This aperture is large enough to permit a wide range of angular disposition of the pipe 2 as will be hereinafter described. On the plate 1 is a riser 3 preferably of copper or other somewhat soft or ductile material. The riser 3 is generally conic and may be a portion of a circular cone or a cone of slightly variant radius. The base of the member 3 is cut at an angle to the normal axis of the cone in one direction, whereas the top of the member 3 is truncated at an angle slightly in the other direction to the axis. The riser 3 is attached to the plate 1 in any usual manner fitting tightly over its aperture.

The member 4 is a collar preferably a rigid casting. At its lower end it slightly flares, having its inner surface beveled off in a cone, the axis of which is skewed to the normal axis of the collar so that its inner surface presents a bevel more acute on one side than on the other. That is to say, it is a cone of variant radius and variant pitch. This gives an internal bearing surface on the lower end of the collar 4 possessing a maximum variety of potential bearing lines in the various secant planes which pass through this bearing zone at different angles to the axis of the collar. This internal bearing surface taken with the external bearing surface of the top of the riser 3 with all of its potential lines of bearing which would be formed by angle secant planes makes a potential mutual bearing possible for almost any pitch of roof. These lines of bearing are generally elliptical in form and of a great variety of shapes according to the angle of the plane of contact between the cap 4 and the top of the riser 3. As above suggested, one or both of the mem-

bers 3 and 4 may be of variant radius in which case the lines of contact would be somewhat more apioidal than elliptical.

I have illustrated in Figs. 3, 4 and 5, three 5 normal roof positions of the joint. In these figures, I have shown the member 4 in three of the several positions into which it may be reversed or partly rotated to get any particular variant in the angle desired.

10 Referring first to Fig. 3, and its corresponding diagram Fig. 3^a, the surface 3^b of the member 3 is shown as bearing upon the surface 4^a of the member 4 throughout a zone *b* which is indicated in said figures by the 15 geometrical figure *c*—*d*—*e*, and the surface 3^a of the member 3 is shown as spaced from the surface 4^b of member 4 throughout the zone *a*.

In Fig. 4, and its corresponding diagram 20 Fig. 4^a, the surface 3^b of the member 3 is shown as bearing upon the surface 4^b of the member 4 throughout a zone *b* which is indicated in said figures by the geometrical figure *f*—*g*—*h*, and the surface 3^a of the member 3 is shown as spaced from the surface 4^a of member 4 throughout the zone *a*.

In Fig. 5, and its corresponding diagram 25 Fig. 5^a, the surface 3^a of the member 3 is shown as bearing upon the surface 4^b of the member 4 throughout a zone *b* which is indicated in said figures by the geometrical figure *i*—*j*—*k*, and the surface 3^b of the member 3 is shown as spaced from the surface 4^a of member 4 throughout the zone *a*.

30 35 These several diagrams illustrate the wide increase in zones possible by working the combinations of the bearings of the two parts.

In order to provide a tightly sealed joint, 40 between the member 4 and pipe 2, the member 4 has an internal shoulder 5 near its upper end defining a packing chamber 6, the wall of which has a slight incline and is provided with a groove 9 for bonding the packing. Lodged within said chamber is a pair 45 of superposed packing rings 7 and 8. The upper ring 8 is a split ring of lead or the like and rests on the lower ring 7, which is a splittable ring of cast iron resting on the shoulder 5. Both rings are beveled, the bevel 50 of ring 7 preferably being at slightly less incline than the wall of the chamber 6, so that the act of pressing the ring 8 down onto the ring 7 forces the ring 7 tightly to its seat on the shoulder 5.

55 Various modifications and adaptations may be used in accordance with the principles of my invention without departing from the spirit thereof as defined in the appended claims.

60 What I therefore claim and desire to secure by Letters Patent is:

1. A roof joint comprising a flexible frustro-conic riser and a rigid collar having an interiorly beveled lower skirt bearing surface of 65 irregular conic section of varying inclination

telescopically fitted upon said riser and independently rotatably adjustable thereon into a position wherein a portion of the zone of mutual bearing contact between the riser and the bevelled skirt of the collar occupies a secant plane which is generally horizontal. 70

2. A roof joint comprising a frustro-conic riser and a collar having an interiorly beveled lower skirt bearing surface of irregular conic section of varying inclination telescopically fitted upon said riser and independently rotatably adjustable thereon into a position wherein a portion of the zone of mutual bearing contact between the riser and the bevelled skirt of the collar occupies a secant plane which is generally horizontal, said collar having an upper packing receiving portion interiorly thereof. 75

80 85 90 95 3. A roof joint comprising a substantially frustro-conical riser and a cylindrical collar adapted to be loosely and rotatably engaged at its lower end over the upper end portion of the riser, the lower end portion of the collar being substantially conically flared with the axis of said conical portion inclined relative to the axis of the collar, whereby with the axis of the collar disposed at any given inclination with respect to the axis of the riser within predetermined angular limits the collar is rotatable to a position in which the lower flared end portion thereof has substantially continuous surface contact with the riser throughout the circumference of the riser and the collar. 100

105 110 115 120 4. A roof joint comprising a frustro-conical riser all surface portions of which have different cone angles, and a cylindrical collar adapted to be loosely and rotatably engaged at its lower end over the upper end portion of the riser, the lower end portion of the collar being conically flared with the axis of said conical portion inclined relative to the axis of the collar, and all parts of said conically flared portion having different cone angles, whereby with the axis of the collar disposed at any given inclination with respect to the axis of the riser within predetermined angular limits the collar is rotatable to a position in which the lower flared end portion thereof has substantially continuous surface contact with the riser throughout the circumference of the riser and the collar. 125

In testimony whereof I affix my signature.
JOHN LEO SCHALLER.
